SPRING CONSTRUCTION

Floyd S. Laurie, Royal Oak, Mich., assignor to
 American Metal Products Company, Detroit,
 Mich., a corporation of Michigan

Application June 18, 1949, Serial No. 99,925

1 Claim. (Cl. 155—179)

1

This invention relates to spring constructions embodying zigzag or sinuous spring strips of the type disclosed and claimed in Kaden Re-issue Patent No. 21,263.

Spring constructions of the type referred to have become increasingly popular in recent years because of their economy in manufacture and also because of the diversity of spring characteristics and cushioning effects which can be obtained with them by altering the nature of the individual spring strips. The present invention constitutes another development in sinuous spring strips which further emphasizes the aforementioned features of economy and diversity of spring characteristics, it being the particular object of the invention to provide a helper spring for stiffening the load supporting portion of a sinuous spring strip.

The invention is illustrated in the accompanying drawings in which:

Figure 1 is a perspective view of a seat end back spring cushion construction with a part of the back broken away to reveal a strip constructed according to the principles of this invention;

Fig. 2 is a front elevation of the back cushion of Fig. 1 with the fabric and covering material removed to show a plurality of spring strips of the invention attached to upper and lower support rails; and

Fig. 3 is a cross section taken on line 3—3 of Fig. 2.

The body rest construction 1 of Fig. 1 comprises a seat cushion 3 and a back cushion 5, each of which preferably contains spring strips embodying features of this invention. In the back cushion, which is selected to illustrate one application of the present invention, the sinuous or zigzag strips 7 are, in the conventional manner, parallel and laterally spaced and each connected at its ends to the top and lower support rails 9 and 11, respectively, of the back panel 12 by insertion of the endmost lateral straight portions of the strips in suitable spring supporting clip strips 13 that are tightly secured to the rails.

The strips 7 are made of two pieces of sinuous strips which are pre-arched and constructed in accordance with the aforementioned Kaden Re-issue Patent No. 21,263. The first strip 15 has a web 17 and integral supports for the web 17 which each comprise an inwardly bent arm 19 and then an arm 21 which is outwardly and reversely bent from the arm 19 and secured by the strips 13 to the rails 9 and 11 in the manner

2

already described. The web 17 is arched so as to provide a crown or downwardly presenting arc, though, as shown by the dotted lines, it is originally pre-arched on a smaller radius than that which it has after assembly to the rails. The arms 21 also preferably are formed to provide downwardly presenting arcs, but the arms 19 are preferably straight or upwardly presenting in the strip 15 per se.

10 The second member of the strip 7 is the helper spring 21. This member, which is of approximately the same length as the web 17, is, as shown in dotted lines, pre-arched on a smaller radius than that which it has after assembly to spring 15. Intermediate portions of the helper spring 21 are secured by clips 29 to the web 17 so that the helper spring continuously engages the underside of the major load supporting portion of the web 17. The ends of the helper spring 21 are secured by clips 31 to intermediate points of the arms 19, these connections preferably being made in such a manner as to reverse the crown of the arms 19 whereby they assume the shape of downwardly presenting arcs.

15 25 It will now be recognized that the helper spring 21 serves to stiffen the load supporting portion of the web 17, i. e., the portion between clips 29, and yet permits the end portions of the web 17 beyond the clips 29 to remain relatively soft.

20 30 The degrees of stiffening and softness remaining can, of course, be regulated by varying the spacing of the clips 29 and by varying the proximity of the clips 31 to the ends of the web 17, the guiding consideration being that softness increases as the radius of curvature or flatness of the helper spring.

35 40 While the preferred form of spring strip 7 has been illustrated, it will be appreciated that the helper spring 21 may be used in conjunction with other forms of springs 15, hence it is not intended to limit the invention to the specific structure herein shown.

What is claimed is:

45 A sinuous spring strip comprising a first spring member made of wire bent back and forth in sinuous form having a web and integral supports for the web bent in the shape of a V thereunder, one of said supports comprising a first portion continuous with the web that is reversely 50 bent inwardly under the web and a second portion reversely bent outwardly from the first portion and adapted at its end to be secured to a rail, and a second helper spring member also made of wire bent back and forth in sinuous 55 form for stiffening the load supporting portion

of the web disposed on the underside of the web and secured to an intermediate portion thereof and having end portions secured to intermediate points of the support, both said helper spring and said web being in the form of downwardly presenting arcs, said helper spring connection with the one support being to an intermediate point of the first portion, when connected to the web the length of the helper spring portion included between the web and the first portion of the one support being less than the distance between the first portion and web without such connection whereby said connection of the first portion and helper spring results in upward crowning of the first portion, the first portion thus being in the form of a downwardly presenting arc.
